(57) CLAIM

The ornamental design for a collectible holder and display, as shown and described.

DESCRIPTION

FIG. 1 is a front elevational view of a collectible holder and display which embodies the design, the items shown in broken lines within the collectible holder and display reflect objects on display and depicted for illustrative purposes only and form no part of the claimed design;

FIG. 2 is a rear elevational view of a collectible holder and display which embodies the design of FIG. 1;

FIG. 3 is a left end perspective view of a collectible holder and display of FIG. 1;

FIG. 4 is a right end perspective view of a collectible holder and display of FIG. 1;

FIG. 5 is a top plan view of a collectible holder and display of FIG. 1; and,

FIG. 6 is a bottom plan view of a collectible holder and display which embodies the design of FIG. 1.
